UNITED STATES PATENT OFFICE.

HARRY J. ROEBUCK AND CLAYTON A. ROEBUCK, OF TROY, NEW YORK.

EXTENSION-STEP.

1,118,584.

Specification of Letters Patent. Patented Nov. 24, 1914.

Application filed March 28, 1914. Serial No. 827,841.

To all whom it may concern:

Be it known that we, HARRY J. ROEBUCK and CLAYTON A. ROEBUCK, of 7 Balsam avenue, Troy, New York, have invented a new and useful Improvement in Extension-Steps, which invention is fully set forth in the following specification.

The present invention relates to extension steps, and has for its objects to provide a simple and effective step of the character described, which may be readily put in place and removed, and which will be certain and efficient in operation.

The step is especially adapted for use on automobiles in connection with which it has been experienced that many people, usually the aged and infirm, cannot step from the ground onto the running board which is usually fifteen or sixteen inches from the ground. The device of the present invention, secured to the under side of the running-board, obviates the inconveniences caused by this condition of things, and presents a perfectly secure step from which one may readily mount to the running board.

It is a matter of great importance to fixedly maintain the step in its extended position, and to that end there are provided by the present invention means for automatically latching the parts in extended position and holding them in that position against accidental displacement.

The invention will be better understood by reference to the accompanying drawings, wherein—

Figure 1 is a side view of part of an automobile, showing the step in place and in extended position; Fig. 2 is a perspective view of the improved step; Fig. 3 is a transverse section, partly in elevation, the parts being in extended position; and Fig. 4 is a similar view, the parts being shown in collapsed position.

Referring to the drawings, wherein like reference numerals refer to like parts, 5—5 indicate guide members which are secured to the underside of the running-board 6 of the vehicle in any desired manner, as by the use of fastening elements 7 and screws passing through holes 8. Suitable supporting members 9—9 are pivoted to said guide members at 10, and a step 11 is mounted on the lower ends of said supporting members. As here shown, said step is pivoted at 12 and rests upon inturned ends 13 of said

supporting members when the step is in position for use. A bracing member 14 is associated with each supporting member 9 and one end of each of said bracing members is pivoted to its associated supporting member at 15. A rod 16 passes through the other ends of said bracing members, and each extremity of said rod engages in a slot 17 provided in each side-piece 18, which latter is preferably, though not necessarily, formed integrally with its corresponding guide member 5. Each slot 17 is provided at one end with an offset 19 (Fig. 4), in which rod 16 engages when the step is in extended position. When the parts are in the extended position (shown in Figs. 1, 2 and 3), the free ends of said bracing members 14 are caused to engage suitable shoulders or abutments 20 (Fig. 3) in order that the parts may be firmly held in that position. As here shown, said shoulders are formed on guide members 5, one being provided on each of said members. Preferably the ends of the bracing members 14 that engage said shoulders are beveled, and when said ends are caused to engage said shoulders the extremities of rod 16 are moved into offsets 19.

It is of the greatest importance that the step should be fixedly secured in extended position and that all danger of accidental displacement be obviated. To this end means have been provided to positively force the beveled ends of bracing members 14 against shoulders 20 and to hold said members so engaged. The particular embodiment of means herein shown comprises a yielding or resilient cam member 21 that is suitably secured to the underside of the running-board between the guide members 5—5 and in a position to engage rod 16 as the parts are moved to their extended position. The resilient cam member engages the rod 16 before the latter reaches the shoulders 20, with the result that, when said shoulders are reached, the beveled ends of bracing members 14 are positively moved into engagement therewith and held there by said resilient member.

In Fig. 4 the parts are shown in collapsed position, being thus held by any suitable means. As herein shown, a spiral spring 22 is connected at one end to a lug 23 secured to the running-board, and at its other end to a strap 24 which carries a ring 25 adapted for engagement with a hook 26 also secured to the running-board. Said strap

passes under the step member 11 and securely holds the parts in their collapsed position.

When it is desired to use the step, ring 25 is first disengaged from hook 26, after which 5 the operator preferably seizes the step member 11 and pulls the same outwardly. This causes the beveled ends of bracing members 14 to slide along the guide members 5 until they are forced into engagement with shoulders 20 by cam member 21, the ends of rod 16 being moved at the same time into offsets 19. The connection of the bracing members 14 with the supporting members 9 is such that the greater the weight applied 10 to step member 11, the tighter will the beveled ends of bracing members 14 grip the shoulders 20, thus eliminating all danger of accidental displacement of the step when 15 it is in use.

20 While for the purpose of clearness, one expression of the inventive idea has been described and illustrated with great particularity, it is to be understood that the invention is not limited to the particular means 25 shown but that the inventive idea is susceptible of other mechanical expressions within the limits of the appended claims.

What is claimed is:—

1. In an extension step, the combination 30 of a pair of guide members each of which is provided with a slotted side piece, said slots having an offset at one end, and each of said members being also provided with a shoulder, a supporting member pivoted to each of said guide members, a bracing member pivoted at one end to each supporting member, a rod passing through the other end of each bracing member, the free ends of said rod engaging in the slots in said side 35 pieces, a step member pivoted to said supporting members, and a yielding cam mem-

ber adapted to engage said rod to force the free ends of said bracing members against said shoulders and the free ends of said rod into said offsets. 45

2. In an extension step, the combination of a pair of guide members, each of which is provided with a shoulder and with a slotted side-piece, a supporting member pivoted to each of said guiding members, a 50 bracing member pivoted at one end to each supporting member, a rod passing through the other end of each bracing member, the free ends of said rod engaging in the slots in said side pieces, a step member pivoted to said supporting members, and a cam member adapted to engage said rod to force the free ends of said bracing members 55 against said shoulders and hold them there.

3. In an extension step, the combination 60 of a pair of pivoted supporting members, a step member pivoted thereto, a bracing member pivoted at one end to each of said supporting members, a shoulder against which the other end of each of said bracing members is adapted to engage, a rod connecting 65 said bracing members, an offset in which each end of said rod is engaged when the parts are in extended position, and a yielding cam member adapted to engage said rod 70 to force the free ends of said bracing members against said shoulders and the free ends of said rod into said offsets.

In testimony whereof we have signed this 75 specification in the presence of two subscribing witnesses.

HARRY J. ROEBUCK.
CLAYTON A. ROEBUCK.
